US0D1029010S

(12) **United States Design Patent** (10) Patent No.: **US D1,029,010 S**
(45) Date of Patent: ** May 28, 2024

(54) **DISPLAY SCREEN OR PORTION THEREOF WITH GRAPHICAL USER INTERFACE**

(71) Applicant: **Chainalysis, Inc.**, New York, NY (US)

(72) Inventors: **Patrick Curran**, Silver Spring, MD (US); **Michael Gronager**, Miami, FL (US); **Jacob Illum**, Ellicott City, MD (US); **Monica Santos**, New York, NY (US); **Pankaj Singh**, Hovedstaden (DK)

(73) Assignee: **Chainalysis, Inc.**, New York, NY (US)

(**) Term: **15 Years**

(21) Appl. No.: **29/864,440**

(22) Filed: **May 27, 2022**

(51) LOC (14) Cl. **14-04**

(52) U.S. Cl.

USPC **D14/487**

(57) **CLAIM**

The ornamental design for a display screen or portion thereof with graphical user interface, as shown and described.

DESCRIPTION

The FIGURE is a front view of a display screen or portion thereof with graphical user interface showing our new design.

The peripheral uneven-length broken lines illustrate a display screen or portion thereof, and form no part of the claimed design. The even-length broken lines within the peripheral uneven-length broken lines illustrate portions of the graphical user interface and form no part of the claimed design.

1 Claim, 1 Drawing Sheet
